Des. 185,294
Patented May 26, 1959

185,294

CHORD ORGAN OR SIMILAR ARTICLE

Finn H. Magnus, Essex Fells, N.J., assignor to Magnus
Organ Corporation, Livingston, N.J., a corporation of
New Jersey

Application August 29, 1958, Serial No. 52,450

Term of patent 14 years

(Cl. D56—2)

Fig. 1 is a front perspective view of a chord organ showing my new design;

Fig. 2 is a front elevational view thereof;

Fig. 3 is a right end elevational view thereof;

Fig. 4 is a top plan view thereof; and

Fig. 5 is a rear elevational view thereof on a reduced scale.

I claim:

The ornamental design for a chord organ or similar article, substantially as shown.
